UNITED STATES PATENT OFFICE.

MIKE HLUSTIK, OF SOUTH BROWNSVILLE, PENNSYLVANIA.

BAYONET-PROJECTOR.

1,265,780.

Specification of Letters Patent.

Patented May 14, 1918.

Application filed September 12, 1917. Serial No. 191,006.

To all whom it may concern:

Be it known that I, MIKE HLUSTIK, a citizen of the United States, residing at South Brownsville, in the county of Fayette and State of Pennsylvania, have invented new and useful Improvements in Bayonet-Projectors, of which the following is a specification.

This invention relates to new and useful improvements in bayonets, and the principal object of the invention is to provide means for projecting the bayonet into the foe without moving the gun.

Another object of the invention is to provide a trigger for releasing the projecting means and to locate said trigger at a point adjacent the trigger guard where it can be easily reached and operated by the trigger finger.

20 A further object of the invention is to provide simple means for moving the bayonet back to its normal position and also to provide means for retaining the bayonet in its extended position.

25 Another object of the invention is to provide a device of this character which is simple and durable in construction, reliable and efficient in operation and one which can be manufactured and placed upon the market 30 at a minimum cost.

The invention also consists in certain other features of construction and in the combination and arrangement of the several parts, to be hereinafter fully described, illustrated 35 in the accompanying drawings and specifically pointed out in the appended claim.

In describing my invention in detail, reference will be had to the accompanying drawings wherein like characters denote like 40 or corresponding parts throughout the several views, and in which:—

Figure 1 is a view of a rifle with the bayonet in extended position.

Fig. 2 is a like view with the bayonet in 45 its retracted position.

Fig. 3 is a longitudinal sectional view.

Fig. 4 is detail of the trigger arrangement.

In these drawings 1 represents the rifle barrel, to the under side of which I secure a 50 tubular casing 2 which is adapted to receive the operating parts of my invention. In carrying out my invention I secure the bayonet 3 to a rod 4 by means of a socket 5 on the bayonet which receives the end of said rod 55 and said parts are held together by the bolt 6. The rod 4 is located within the casing 2

with its end projecting therefrom to receive the bayonet. At its rear end said rod is provided with an enlargement 7 and adjacent said enlargement a stem 8 is secured to 60 the rod and carries a knob 9. The casing 2 is provided with a slot 10 through which said stem projects with the knob outside of the casing. At its forward end said slot is provided with a downwardly projecting 65 part 11 to receive said stem. 12 represents a coil spring engaging a collar 13 on the inner part of the casing 2 and having its other end bearing against a collar 14 on the rod 4. Thus said spring tends to 70 hold the rod in its forward position with its end projecting from the casing a considerable distance beyond the end of the rifle. A trigger 15 is pivoted to the rifle, as at 16, and has its end 17 located adjacent the trigger 75 guard 18 of the rifle. Said trigger has its forward end provided with an engaging lug 19 which is adapted to engage with the enlargement 7 on the end of the rod 4. Said lug is provided with an inclined outer face 80 so that said enlargement may ride over the same when the rod 4 is pushed rearwardly thereagainst so that said lug will move downwardly to permit the enlargement to pass the same, and a spring 20 will force 85 said lug upwardly into engagement with said enlargement to hold the spring 12 compressed. It will be understood that the rod is moved to its retracted position by grasping the knob 9 on the stem 8. 90

When the soldier comes to close quarters with his foe and the bayonet is to be used he will hold the rifle in a position with the bayonet pointing at his foe, then by pressing upon the trigger said trigger will release 95 the enlargement 7 and the spring will cause the rod to spring forwardly, thus embedding the bayonet in the body of the enemy. If the bayonet should fail to reach the enemy, the soldier may still use his rifle in the ordinary way and he will have an advantage 100 over his foe, due to the fact that the bayonet is of much greater length than that ordinarily used. Said bayonet is held in its extended position by reason of the fact that the 105 stem 8 is held in the part 11 of the slot, thus preventing the rod from moving inwardly, it being understood that the coil spring will give the rod a slight turning movement to force said stem into said extended part of 110 the slot. When the bayonet is to be retracted it is simply necessary to grasp the knob

2
and give it a slight movement upwardly to take it out of the part 11 of the slot and then pull it toward the rear end of the rifle until the enlargement 7 engages with the trigger.

It will be seen that when desired the bayonet may be detached from the rifle as in ordinary guns.

It is thought from the foregoing description that the advantages and novel features of my invention will be readily apparent.

I desire it to be understood that I may make slight changes in the construction and in the combination and arrangement of the

several parts, provided that such changes fall within the scope of the appended claim.

What I claim is:—

The combination with a rifle, of a casing located below the same, a rod movably mounted in said casing, a bayonet connected with the end of said rod, a trigger pivoted to the rifle and having a part engaging with said rod to hold the same in retracted position, and a second part located adjacent the trigger guard of the rifle.

25
In testimony whereof I affix my signature.

MIKE HLUSTIK.
